UNITED STATES PATENT OFFICE.

JONATHAN D. MAXWELL, OF TARRYTOWN, NEW YORK.

DESIGN FOR AN AUTOMOBILE-BODY.

No. 38,691.

Specification for Design.

Patented July 16, 1907.

Application filed June 19, 1907. Serial No. 379,818. Term of patent 14 years.

To all whom it may concern:

Be it known that I, JONATHAN D. MAXWELL, a citizen of the United States of America, residing at Tarrytown, in the county of Westchester and State of New York, have invented a new, original, and ornamental Design for Automobile-Bodies, of which the following is a specification, reference being had therein to the accompanying drawing, forming a part thereof, in which my new design is shown in perspective view.

I claim:

The ornamental design for automobile body as shown.

JONATHAN D. MAXWELL.

Witnesses:

J. T. CONNELL,

A. L. JACKSON.
